MERCURY SWITCH

Milton W. Griffes, Cleveland, Ohio, assignor to
 The Electric Controller & Manufacturing Company, Cleveland, Ohio, a corporation of Ohio

Application May 21, 1942, Serial No. 443,848

17 Claims. (Cl. 200—33)

This invention relates to mercury flow switches, and more particularly to mercury switches in which the mercury is caused to flow by gravity or other means and which provides a variable time delay either in the opening or in the closing of a circuit through the switch.

Heretofore, the time required to operate hermetically sealed, gravity operated mercury switches of the tubular type has been varied by adjustment of the initial inclination of the longitudinal axis of the switch. By means of such adjustment the rate of flow of mercury through an orifice of definite size was controlled by variations in the pressure head due to the angle of inclination of the axis of the tube.

In many installations, however, it is either undesirable to vary the angle of initial inclination of the switch, or, due to the small total angle through which the switch is tilted for operation, impossible to do so and obtain a satisfactory range of time adjustment for most purposes. For example, it is desirable to control the successive operation of electromagnetic contactors by time delay mercury switches driven directly by the contactor shafts. Since the total angle of rotation of such shafts is seldom greater than ten degrees, it is apparent that possible adjustments of the initial inclination of the switch cannot provide either a wide range or accuracy of time variation.

In accordance with this invention, two means are provided which may be used singly or in combination to effect variations of the time delay period of a hermetically sealed, tubular mercury switch depending upon the axially rotated position of the switch. One of the two means comprises a valvular septum containing a plurality of different sized orifices spaced apart near its periphery, and mounted trans-axially of the tube which forms the switch body so as to divide the tube into two chambers. By adjustment of the axial rotated position of the tube, the orifice, or orifices of the desired size can be disposed lowermost. The rate of flow of mercury from the first chamber into the second chamber through the valvular septum depends upon the size of the orifice or orifices through which it flows. The time required for a given amount of mercury to flow from one chamber to the other and complete or break the circuit is, therefore, predetermined by adjustment of the "axial rotated position" of the tube; that is, the position to which the tube, or the septum therein, is rotated about its longitudinal axis. The range of time adjustment available by pre-selection of orifice size alone is some-

what limited in switches of small diameter since, due to the inability of mercury to flow through extremely small openings, only a limited number of different sized orifices can be utilized.

5 The other of the two means by which the time adjustment of a switch is affected is by pre-selection, by adjustment of the axial rotated position of the tube, of the amount of mercury which must flow through the septum in order to open or close 10 a circuit through the switch. In one embodiment of the invention, said other means comprises a chamber into which the mercury flows through an orifice in the septum, the chamber being defined by the septum and an annular shaped piece 15 of refractory material, hereinafter referred to as a breaker, which is mounted obliquely with respect to the longitudinal axis of the tube.

A change in the axial rotated position of the switch effects a change in the amount or volume 20 of mercury which must flow through an orifice before the switch operates, even though the orifices in the septum are of the same size. The "effective volume" of the receiving chamber is therefore adjustable, and "effective volume," as hereinafter used, means that volume of a mercury switch chamber which must be filled by the mercury or from which the mercury must flow before operation of the switch, so that the level of the surface of the mercury is sufficient to make 25 or break contact. Likewise, "effective volume of mercury" is the volume of the mercury which must flow through an orifice to effect operation of the switch.

The principal object of this invention is to provide 30 a new and improved time delay mercury switch.

Another object is to provide a gravity operated, 35 hermetically sealed mercury switch having a time delay period in opening or closing that is both accurate and adjustable throughout a wide range.

Another object is to provide a tubular mercury switch having the duration of a time delay period in opening or closing predetermined by selection 40 of the axial rotated position of the switch.

Still another object is to provide a gravity operated, hermetically sealed, tubular mercury switch having a valve mechanism which regulates the rate of flow of mercury within the switch in accordance with the axial rotated position of the 45 switch.

A specific object of this invention is to provide 50 a tubular mercury switch having a transaxial septum pierced by an orifice means which is eccentric with respect to the axis of the septum and of which different portions, circumferentially with-

respect to said axis, are of different effective area with respect to each other, any portion of which may be selected, by rotation of the switch about its axis, to serve as a passage for the mercury during the timing period of the switch.

Another object is to provide a two chamber tubular mercury switch having the effective volume of one of the chambers variable consequent upon axial rotation of the tube.

A further specific object is to provide a tubular mercury switch having two chambers separated by a transaxial septum containing a plurality of different size orifices one or more of which may be selected for use by axial rotation of the switch and in which the effective volume of one of the chambers is variable consequent upon the same axial rotation of the switch.

Another object is to provide a valve mechanism for a mercury switch which permits retarded flow of mercury therethrough in one direction and which flexes to permit unretarded flow of mercury in the other direction.

Still another object is to provide a hermetically sealed mercury switch having an adjustable time delay and having its parts so designed that the same parts may be used to construct a switch providing a time delay in the closing of a circuit through the switch or a switch providing a time delay in the opening of the circuit.

Another object is to provide an adjustable time delay mercury switch of the hermetically sealed type in which the limits of the range of time delay obtainable is readily selected during manufacture by relative positioning of standard parts.

Other objects and advantages will become apparent from the following specification wherein reference is made to the drawings, in which

Fig. 1 is a longitudinal sectional assembly view showing a preferred switch for closing a circuit after a time delay and illustrating the switch in one of its axial rotated positions and tilted to its normal inoperative position;

Fig. 2 is a longitudinal sectional view of the switch of Fig. 1, partly in elevation and showing the switch tilted to its timing position;

Fig. 3 is an enlarged cross sectional view of the switch and is taken along the line 3—3 of Fig. 1 and shows the valve mechanism;

Fig. 4 is an enlarged central sectional sub-assembly view of the valve and its supporting frame;

Fig. 5 is an elevation, partly in section through the axis of the tube, of the switch when arranged to provide a time delay in the opening of a circuit through the switch;

Figs. 6 and 7 are elevations of modified forms of septums;

Fig. 8 is an elevation, partly in section through the axis of the tube, of the switch showing the switch in the timing position and with a modified terminal arrangement;

Fig. 9 is a sectional view along the line 9—9 of Fig. 8 as viewed from the left, showing the breaker and terminal arrangement;

Fig. 10 is a view similar to Fig. 9 with the switch rotated 180 degrees.

Referring to Figs. 1 and 2, the body of the switch comprises a metal tube 10 closed at one end by an integral wall 11 and open at the other end 12. The open end portion is preferably enlarged in diameter, as by counterboring to somewhat less than half the length of the tube, thus forming an annular shoulder 14. The shoulder positions a suitable valve mechanism 15 com-

prising, as shown, a rigid support 16 and a flexible septum 24. Said mechanism may be secured in the tube by cementing and welding the support 16 to the shoulder 14 and the adjacent counterbore surface. A circular supporting clamp 5 for the tube 10 has a projecting bracket 6 attached, as by a pin 8, to a bracket 7. The latter may be a part of an electromagnetic contactor arm. A bolt and wing nut assembly 9 of the clamp 5 permits the tube to be adjustably secured in different rotated positions about its longitudinal axis.

The support 16 is preferably a spider frame (Figs. 3 and 4) having a rim portion 18 including a flange 17, a hub 19, and spokes 20. The septum 24 is a flat circular disc of flexible material, such as rubber, attached at its center to the hub 19 as by a bolt 26 and a nut 28. A thin washer 29 spaces apart the septum 24 and its support. The diameter of the septum 24 should be slightly less (e. g. $\frac{1}{4}$ inch) than the internal diameter of the closed end of the tube 10.

The septum 24 divides the tube 10 into two chambers 32 and 34. When the tube 10 is tilted to its normal position (Fig. 1) any mercury then in the chamber 34 deflects the flexible septum 24, and flows quickly around the periphery of the septum into the chamber 32. The marginal area of the septum 24 is forced by pressure of the mercury in the chamber 32 to make a tight seal with the rim 18, thus preventing return flow of mercury around the periphery of the septum 24. Return flow (from 32 to 34) is controlled by a variable orifice means of the septum 24 arranged to be decrescent in effective size circumferentially of the septum. This variable orifice means may be considered to comprise an elongated circumferential slot of decrescent radial width in which case the area of the orifice means within any given sector is or would be of different effective size from the area within an equal but angularly displaced sector. For practical purposes, a circumferential series of openings of progressively decrescent size form, in effect, such a slot and do not materially weaken the septum. Such openings 30a, 30b, 30c and 30d, as shown by Fig. 3, are of increasing area in the order named and circumferentially spaced along slightly more than one-half of the periphery of the septum 24, permitting the flow of mercury from the chamber 32 into the chamber 34.

By rotating the septum 24 about its axis, orifice means of selected sizes may be positioned at the lowermost portion of the tube thereby to control the rate of return of the mercury therethrough into the chamber 34. Rotation of the septum, in the illustrative example, is accomplished merely by rotating the tube about the septum axis.

The open end 12 of the tube 10 may be closed by a thimble shaped piece of insulation 36 secured to and surrounding a terminal 38, the inner end of which is beveled to form an oblique face 39. The outer end of the terminal rests tightly against the closed end of the thimble 36 so that the side wall of the thimble projects beyond the beveled face 39.

The open end of the thimble 36 is oblique with respect to its longitudinal axis and is closed by a flat annular breaker 42 of arc resisting material such as porcelain or lava. The breaker, as shown, has a central circular opening 37 and outer peripheral surfaces parallel thereto; the latter fitting the counterbore of the tube 10 in

the oblique position of the breaker shown. The breaker is secured, as by cement, to the inner end faces of the thimble 36 and to the inner wall of the tube 10. As shown in Figs. 1 and 2, the breaker 42 and the oblique face 39 of the terminal 38 may be parallel with each other and spaced apart a short distance to permit a stationary pool 41 of mercury to be retained therebetween. Although the oblique face 39 of the terminal 38 and the face of the breaker 42 are shown to be planular, it is obvious that they could be curved surfaces as well. For example, a logarithmic configuration of these faces causes the adjustment of the switch to be logarithmic in nature.

10 A suitable gas-tight seal is made between the tube 10 and the thimble 36 and the ends of the tube 10 are spun over as at 40 to secure the thimble 36 in place. Before the tube 10 is sealed, a quantity of mercury is placed therein and the tube 10 is either evacuated or evacuated and filled at super-atmospheric pressure with a suitable ionization resisting gas such as hydrogen or neon as is common in the art. It is desirable that the quantity of mercury in the switch be greatly in excess of the amount required to provide a circuit between the terminal 38 and the tube 10.

15 For simplicity and economy, one terminal of the switch may be formed by the tube 10 to which a flexible conductor 48 may be attached, and the other terminal 38 may be connected to a flexible conductor 50 as by fitting the end of the conductor 50 into a hole drilled through the base of the thimble 36 and into the terminal 38.

20 When the switch is in the position shown in Fig. 1 a main body 43 of mercury is in the chamber 32 and its surface is below the lowermost portion of the orifice means in the septum 24. When the left end of the tube 10 is raised approximately ten degrees to the position shown in Fig. 2, some of the mercury of the body 43 in the chamber 32 flows into the chamber 34 through the lowermost portion of the orifice means which, in the illustrative example, is the orifice 30d in the septum 24. Although when the tube 10 is first moved to the position of Fig. 2 more than one orifice in the septum 24 may be below the surface of the mercury 43, mercury generally flows only through the lowermost orifice because the fluid characteristics of mercury are such that considerable pressure head is required to cause it to flow through small openings. If the mercury does flow through more than one orifice in a given position of the switch, the time delay period is predetermined because of the sizes of the orifices and their respective depths below the surface are preselected. Due to that phenomenon of mercury flow, the series of orifices provides a substantially uniformly increased or decreased flow for changes in rotated position, about the same in effect as a continuous slot of uniformly decrescent width from one end to the other. When sufficient mercury is in the chamber 34 to overflow through the opening 37 in the breaker 42, electrical contact is made with the pool 41 of mercury retained between the breaker 42 and the terminal 38.

25 If the axial rotated position of the tube 10 is such that the portion of the breaker 42 closest to the septum 24 is lowermost during the timing operation, the effective volume of the receiving chamber 34 is a minimum, and only a relatively small quantity of mercury need pass from the chamber 32 into the chamber 34 before it overflows through the opening 37 and makes contact with the mercury pool 41. If the tube 10 is

30 rotated 180 degrees so that the portion of the breaker 42 farthest from the septum 24 is lowermost, the effective volume of the receiving chamber 34 is a maximum and a large amount of mercury must flow into the chamber 34 before it overflows through the opening 37. Rotation of the tube to intermediate positions changes the effective volume of the receiving chamber depending upon the axial rotated position selected.

35 Thus timing may be adjusted upon rotation of the tube 10 by either of two means, one being the rotated position of the orifice means and the other being the rotated position of chamber 34. By combining the two, as in the present example, a much wider range can be obtained than with either alone. As shown in Figs. 1, 2 and 3, the septum 24 and the thimble 36 have been so mounted in the tube 10 that when the tube 10 is rotated to a given zero position, the orifice 30d, which is the largest of the orifices in the septum 24, is at the bottom of the tube 10 and the portion of the breaker 42 closest to the septum 24 is also at the bottom of the tube 10. Under these conditions the rate of the flow of mercury through the orifice 30d is a maximum, and the total amount of mercury which must flow to cause operation of the switch is a minimum. Therefore, the time delay interval of the switch is a minimum. If the tube 10 is rotated 180 degrees about its longitudinal axis, the smallest orifice 30a is at the bottom and the portion of the breaker 42 farthest from the septum 24 is lowermost. Under those conditions, the time delay period of the switch is a maximum since the largest amount of mercury must flow from the chamber 32 through the smallest orifice 30a before the circuit through the switch is completed. It is obvious that if the switch is rotated to positions intermediate the zero position and the 180 degree position, intermediate values of time delay are obtainable. On the other hand, if a wide angle of rotation for a slight increment of adjustment is desired, the septum 24 can be installed in a rotated position such that the largest effective volume of the chamber 34 and the largest portion of the orifice means cooperate.

40 Switches providing various limits of time ranges and timing periods may be constructed merely by altering the distance between the valve mechanism 15 and the thimble 36, as by changing the depth of the counterbore which forms the shoulder 14. The adjustment possible by so determining the position of the shoulder is limited however by the obvious relationship between the actual volume of the chamber 32, the quantity of mercury in the switch, and the various effective volumes of the chamber 34.

45 In order to interrupt the circuit through the switch the tube 10 is tilted back to the position of Fig. 1, whereupon substantially all of the mercury in the chamber 34 flows into the chamber 32 in an extremely short time as previously described.

50 A modified form of septum which may be substituted for the septum 24 is shown at 52 in Fig. 6, and has a plurality of equal sized orifices 54a, 54b, 54c, 54d and 54e uniformly spaced about one half of its periphery. When the septum 52 is substituted for the septum 24, the adjustment of the time delay of the switch is due only to the variation in the effective volume of the receiving chamber 34 consequent upon adjustment of the axial rotated position of the tube 10, and is not due to a difference in the rate of flow of the mercury through an orifice.

A septum 56 shown in Fig. 7 is also similar to the septum 24 and may be substituted therefor. In switches of small size the number of orifices which may be placed near the periphery of one-half of the septum is limited, and, therefore, the range of time adjustment may not be as great as desired for some applications. The septum 56 has orifices 58a, 58b, 58c, 58d and 58e circumferentially spaced about slightly more than one-half of its periphery and which are graduated from an extremely small size to a large size, and a plurality of orifices 59a, 59b and 59c, circumferentially spaced about the other half of the periphery and having sizes intermediate those of adjacent orifices 58a, 58b, 58c, 58d and 58e. When the septum 56 is used in place of the septum 24, almost twice as many steps of time adjustment are rendered available due to the fact that the time delay adjustment effected by the oblique face 39 of the terminal 38 and the obliquely mounted breaker 42 is not dependent upon the unidirectional axial rotation of the tube 10 from the position shown in Fig. 1.

The switch of Fig. 5 is the same as that of Fig. 1 and Fig. 2 but is assembled to provide a time delay period in the opening of an electric circuit. This reverse timing operation is obtained by mounting the septum 24 on the right instead of the left side of the support 16. The reversal of the position of the septum 24 causes the controlled flow of mercury from the chamber 34 into the chamber 32 to be retarded and permits the flow of mercury from the chamber 32 into the chamber 34 to be unimpeded. If the axial rotated position of the tube 10 is such that the chamber 34 has its largest effective volume and the tube 10 is in the horizontal position, a long time is required for sufficient mercury to flow from the chamber 34 into the chamber 32 to result in interruption of the circuit between the tube 10 and the terminal 38. Rotation of the tube 10 of the switch of Fig. 5 about its longitudinal axis changes the effective volume of the chamber 34 as before so that a different predetermined amount of mercury must flow from the chamber 34 to cause opening of the circuit through the switch. The switch of Fig. 5 is reset by raising the closed end 11 of the tube 10 about ten degrees which causes a rapid flow of mercury from the chamber 32 into the chamber 34 around the periphery of the deflected septum 24.

The modified septa shown in Figs. 6 and 7 may be substituted for the septum 24 shown in Fig. 5. The inside diameter of the annular flange 17 is the same as the inside diameter of the closed end of the tube 10 and therefore a septum of the same diameter can be used for both the normally open and the normally closed types of switches.

The oblique disposition of the breaker and terminal face may be obviated by a construction such as shown in Figs. 8, 9 and 10. As there illustrated, a right angled cylindrical block 61 of insulating material is sealed in the open end 12 of a tube 60, which is similar to the tube 10 except that it is shorter and consequently the shoulder 14 is closer to the open end 12. The block 61 has a central opening 62 which merges into a counterbored portion 64 defining a flange 72 extending inwardly of the tube 60. A threaded stem 66 having a head 68 which serves as a circuit terminal extends through the opening 62 and the head 68 fits snugly into the counterbored portion 64 and its shoulder abuts against the block 61 in the bottom of the counterbored portion 64. Nuts 78 may be threaded on the stem 66 to hold the

stem in place, to provide a fastening for a flexible conductor (not shown), and to expand the block 61 and thereby assist in making a gas tight seal after mercury has been placed in the tube.

- 5 A suitable breaker 70 is secured against the edge of the flange 72. An eccentric opening 74 through the breaker 70 opens into a chamber 76 between the head 68 and the breaker 70 in which the pool 41 of mercury is retained. Due to the eccentricity 10 of the opening 74, the chamber 34 has a variable effective volume depending upon the rotated position of the tube 60. If the switch is in the position shown in Fig. 8, the effective volume of the chamber 34 is indicated by the dotted line 77 of Fig. 9. If the tube 60 is rotated 180 degrees, the effective volume of the chamber 34 is indicated by the dotted line 78 of Fig. 10. Intermediate values of effective volume are obtained if the tube 60 is rotated less than 180 degrees.
- 15 20 The valve mechanism 15 of the embodiments of Figs. 8 to 10 may be arranged as shown in Fig. 1 or as shown in Fig. 5 depending upon whether time delay action is required in the opening or in the closing of a circuit through the switch.
- 25 If a time delay in both opening and closing of the circuits through any of the described switches is desired, the septum can be made rigid or two reversed septa can be utilized.

I claim:

- 30 1. An adjustable time delay, mercury flow switch comprising an envelope having two chambers from each of which mercury can flow into the other, a quantity of mercury therein for rendering the switch operative to open and close a circuit through the switch upon predetermined distribution of the mercury in said chambers, means operatively interposed between the chambers and having an axis normally disposed at an angle to the vertical and operative 35 to vary the rate of flow of mercury from one of said chambers into the other dependent upon the position to which said means is rotated about its axis, said means and envelope being secured for rotation together about said axis, whereby 40 control of the mercury flow may be obtained by rotation of the envelope about said axis, and means supporting the envelope for rotation about said axis.

2. In a mercury flow switch, the combination 50 with an envelope having two substantially co-axial aligned chambers from each of which mercury can flow into the other and a quantity of mercury in said envelope for rendering the switch operative to open and close a circuit upon predetermined distribution of the mercury in said 55 chambers, of means operable to permit retarded rate of flow of mercury from one of said chambers into the other of said chambers at a rate, when the axis of the chambers is at an angle to an upright position, dependent upon the position to which said envelope is rotated about said axis, and means supporting the envelope with said axis at an angle to the vertical.

3. An adjustable time delay mercury switch in 60 which mercury flows from one chamber to another and the operation of the switch is dependent upon the volume of mercury in one of the chambers and comprising a hollow body containing mercury, a wall dividing the body into a pair 65 of substantially co-axial aligned chambers and having an orifice means therein which is eccentric with respect to said axis and of which different portions, circumferentially with respect to said axis, are of different effective area with respect to each other, whereby the rate of flow of

said mercury through said orifice means can be selected by rotation of the body about said axis when said axis is at an angle to the vertical, and means for supporting said body for rotation about said axis.

4. An adjustable time delay mercury switch in which mercury flows from one chamber to another and the operation of the switch is dependent upon the volume of mercury in one of the chambers and comprising a hollow body containing mercury, a wall dividing the body into a pair of substantially co-axial aligned chambers and having an orifice means therein which has a different area exposed to the mercury for different axial rotated positions of said body, whereby the rate of flow of said mercury through said orifice means can be selected by rotation of the body about said axis when said axis is at an angle to the vertical, and means for supporting the body for rotation about said axis.

5. A switching mechanism comprising an envelope, a pair of circuit terminals associated with said envelope, said envelope having an internal passage for mercury to flow to and from one of said terminals, a quantity of mercury in said envelope adapted to complete an electric circuit through said terminals, a flexible septum rigidly supported and extending transaxially of said passage and having its margin free to flex, said septum having an orifice means for permitting retarded flow of mercury through the passage, an annular projection extending from said envelope into said passage near the periphery of said septum, whereby pressure of the mercury on one side of said septum causes the marginal area of said septum to engage said projection to prevent the flow of mercury around said septum and the pressure of the mercury on the other side of said septum causes said septum to flex to permit flow of mercury around said septum.

6. A switching mechanism according to claim 5 characterized in that said orifice means is eccentric with respect to the axis of said passage and of which different portions circumferentially with respect to said axis are of different effective area with respect to each other.

7. An adjustable time delay mercury flow switch comprising a hollow body having a pair of chambers and in which mercury flows from one chamber to the other and operation of the switch is effected when the volume of mercury in one of the chambers is equal to the effective volume of said chamber, mercury in said chambers, one of said chambers having an axis disposed at an angle to the vertical, said one of said chambers having a different effective volume at different rotated positions with respect to its said axis, whereby rotation of said body about said axis when the axis is at an angle to an upright position changes the volume of mercury required to effect operation.

8. A mercury switch comprising a hollow body having a pair of communicating chambers and in which the flow of mercury between the chambers is necessary for operation, mercury in the chambers, means for retarding the flow from one chamber to the other chamber, said switch being rendered operative upon the surface of the mercury in one chamber reaching operating level, one of said chambers having an axis angularly disposed to the vertical, and means operative upon rotation of the last mentioned chamber about said axis to change the amount of mercury required to cause its surface to reach operating level.

9. An adjustable time delay mercury flow switch in which mercury flows from one chamber to another and operation of the switch is effected when the volume of mercury in one of the chambers is equal to the effective volume of said chamber and comprising a hollow body containing mercury, a wall dividing the body into a pair of chambers, one of said chambers having an axis at an angle to the vertical and having a different effective volume at different axial rotated positions, whereby rotation of said one chamber about its said axis when the axis is at an angle to an upright position changes the volume of mercury required to effect operation, said wall having an axis in fixed angular relation to the axis of the chamber, and orifice means in said wall permitting retarded flow of mercury between said chambers at a rate dependent upon the rotated position of the wall about its axis when its axis is at an angle to an upright position.

10. An adjustable time delay mercury switch in which mercury flows from one chamber to another and the operation of the switch is dependent upon a predetermined volume of mercury being in one of the chambers and comprising a hollow body containing mercury, a wall dividing the body into a pair of substantially co-axial aligned chambers and having an orifice means therein which is eccentric with respect to said axis and of which different portions, circumferentially with respect to said axis, are of different effective area with respect to each other, whereby the rate of flow of said mercury through said orifice means can be selected by rotation of the body about said axis when said axis is at angle to the vertical, and means operative upon rotation of the body about said axis for predetermining said volume of mercury required for operation.

11. A mercury flow switch combination according to claim 2 characterized in that the combination includes a pair of circuit terminals associated with said envelope, said mercury being adapted to affect the electrical conduction of a circuit through said terminals upon occurrence of a predetermined relative volume of said mercury in one of said chambers, and a means, operative consequent upon axial rotation of said envelope, for varying said predetermined volume.

12. In a mercury flow switch, a hollow body having a longitudinal axis, a valve member dividing the envelope into two aligned co-axial chambers, a quantity of mercury in one of said chambers, said valve member being operable to permit retarded flow of said mercury from said one chamber to said other chamber when said axis is at an angle to an upright position, a pair of spaced circuit terminals, the level of the surface of the mercury in said other chamber relative to one of said terminals controlling an electric circuit through said circuit terminals, means operative upon rotation of said envelope about said longitudinal axis to predetermine the amount of mercury required to reach said level in said one chamber, and said valve member being operative to permit retarded flow of said fluid at predetermined rates depending upon the axial rotated position of said envelope.

13. An adjustable time delay, mercury flow switch comprising an envelope having two chambers, a quantity of mercury therein for rendering the switch operative to open and close a circuit through the switch upon predetermined distribution of the mercury in said chambers, flow

varying means operatively interposed between the chambers and having an axis normally disposed at an angle to the vertical and operative to vary the rate of flow of mercury from one of said chambers into the other dependent upon the position to which said flow varying means is rotated about its axis, whereby control of the mercury flow may be obtained by rotation of the flow varying means about said axis, and means supporting said flow varying means for rotation about said axis.

14. In a mercury flow switch, the combination with means having two chambers and a passage for fluid connecting the chambers, a quantity of mercury therein, means to retard the flow of said mercury from one of said chambers to the other, and means responsive to a predetermined disposition of said mercury in at least one of said chambers for effecting operation of the switch, of means dependent upon the axial rotated position of said first means to change said predetermined disposition of mercury required for effecting operation.

15. An adjustable time delay mercury switch comprising a hollow body adapted to contain mercury, a wall dividing the body into two substantially coaxially aligned chambers, said wall having a plurality of different sized perforations constituting orifices eccentric to the axis of alignment, said perforations being circumferentially spaced about said axis and located near the peripheral wall of said hollow body, said switch being operable to effect different degrees of time delay by flow of mercury from one cham-

ber to the other through one or more of said orifices as selected by rotation of the body about said axis, and means for supporting the body in a manner enabling such rotation.

5 16. An adjustable time delay mercury flow switch comprising a two-chambered hollow body adapted to contain mercury and in which mercury flows from one chamber to the other and operation of the switch is effected when the 10 volume of mercury in one of the chambers is equal to the effective volume of that chamber, one of the chambers having an axis disposed at an angle to the vertical and having a bounding wall intersecting said axis at an oblique angle whereby rotation of said body about said axis when the said axis is at an angle to an upright position changes the volume of mercury required to effect operation.

15 17. A mercury switch comprising a hollow body adapted to contain mercury, said body having a pair of communicating chambers, said switch being rendered operable by flow of mercury from one chamber to the other and in accordance with the mercury surface level 20 reached in one of the chambers, means for retarding the flow from one chamber to the other chamber, one of said chambers having an axis angularly disposed to the vertical and having an operating portion which is eccentric with respect to said axis and operative upon rotation 25 of the last mentioned chamber about said axis to change the amount of mercury required to cause its surface to reach operating level.
